US0D1077629S

(12) **United States Design Patent** (10) **Patent No.:** **US D1,077,629 S**
(45) **Date of Patent:** **** Jun. 3, 2025**

(54) **FASTENER**

(71) Applicant: **Yiwu Qiufa Toys Co., Ltd**, Jinhua (CN)

(72) Inventor: **Haoliang Huang**, Yichun (CN)

(73) Assignee: **Yiwu Qiufa Toys Co., Ltd**, Jinhua (CN)

(**) Term: **15 Years**

(21) Appl. No.: **29/948,452**

(22) Filed: **Jun. 21, 2024**

(51) LOC (15) Cl. **08-08**

(52) U.S. Cl.

USPC **D8/382**

(58) **Field of Classification Search**

USPC D8/382, 349, 354; D10/121; D6/575,

(57) **CLAIM**

The ornamental design for a fastener, as shown and described.

DESCRIPTION

FIG. 1 is a top perspective view of fastener, showing my new design;

FIG. 2 is a front view thereof;

FIG. 3 is a rear view thereof;

FIG. 4 is a right side view thereof;

FIG. 5 is a left side view thereof;

FIG. 6 is a top view thereof;

FIG. 7 is a bottom view thereof; and,

FIG. 8 is a top perspective view of the fastener, showing a state of use.

The broken lines in the drawings depict portions of fastener, that form no part of the claimed design.

1 Claim, 8 Drawing Sheets
